UNITED STATES PATENT OFFICE.

ALFRED WILLIAMS AND LEO D. WILLIAMS, OF LONDON, ENGLAND.

TELEPHONIC RECEIVER.

1,405,472.

Specification of Letters Patent.

Patented Feb. 7, 1922.

Application filed January 12, 1917. Serial No. 142,009.

To all whom it may concern:

Be it known that we, ALFRED WILLIAMS and LEO DAFT WILLIAMS, both citizens of the United States of America, residing at 16

5 Hauteville Court Gardens, Stamford Brook, London, England, have invented a new and useful Improved Telephonic Receiver, of which the following is a specification.

This invention relates to an improved receiver of the thermophone type, and its object is to enable sounds, including the actual tones of the human voice, or of musical notes, to be plainly and clearly reproduced, and also to render audible electric impulses 10 of any kind, especially those received from wireless transmitters.

It has already been proposed in connection with telephone receivers to make use of the well-known thermophone effect where- 20 in varying electric currents produce corresponding changes in temperature in very fine wires. A method or process of manufacturing metallic filaments or strips for use as heating conductors in thermic telephones 25 has also been proposed, according to which a metallic filament or strip is deposited electrolytically upon a metal support, which support is subsequently removed by corrosion or by being subjected to an electrolytic 30 process.

According to our invention instead of wires we use a bridge of metal foil or leaf preferably gold leaf suspended between supports and thereby we obtain great dis- 35 distinctness in articulation as well as other advantages.

Two methods of carrying out our invention are illustrated in the accompanying drawings.

40 Fig. 1 is an elevation of a single bridge of a simple form. A strip of metal foil F is attached by its ends to two conducting supports A, A.

Fig. 2 is a plan of the same.

45 Fig. 3 is an elevation of a multiple bridge. A, A are two conducting supports, B, B being insulated supports for the metal foil F, F. Where greater length of bridge is required the number of supporting pillars, 50 such as B, may be increased. By placing them in suitable positions many may be put in a small space.

Fig. 4 is an isometric elevation of a helical type of bridge. a, a are two conducting

supports, corresponding with A, A in the other figures, while the edges C of the body act as insulated supports corresponding to the pillars B.

The above represents only series working, but the bridge may be connected in parallel 60 or series-parallel according to the resistance desired.

The effect of a parallel connection may be obtained in a single bridge by using a greater width of metal leaf, but the efficacy 65 of this depends on the strength of the currents available.

The thickness of the leaf used depends on the nature of the metal. We have found that any metal will work provided that the leaf 70 employed can be beaten or rolled out thin enough. Alloys in the form of leaf or foil may be used. The results naturally vary with different kinds of metal leaf, and to get the best results with any particular 75 metal leaf it is advisable to obtain the leaf as thin as possible consistent with its possessing the necessary mechanical strength for practical usage. Silver works very well, aluminum works well, and so does platinum, but we have got the best results by using gold leaf of a thickness of approxi- 80 mately .0000035-.000006 in. which is such that it transmits green light waves and by using gold leaf strips having a width of 85 about one millimetre we have obtained a receiver which reproduces the human voice with remarkable fidelity; yet the bridge has ample mechanical strength to stand vibration and rough usage. One such bridge is 90 sufficient, though several may be used.

The amount of air about the bridge should be as little as possible, and it is best to have the chamber containing the bridge small; but so long as the general principles of 95 acoustics are followed it has been found that the shape of the container is not important.

We claim:

1. In a thermo-telephone receiver, a heating conductor of a metal foil of a thickness 100 of the order of gold leaf which transmits green light and means for supporting it at two points so as to hold the intermediate portion in suspension.

2. In a thermo-telephone receiver, a heating conductor of metal foil of a thickness 105 of the order of gold leaf which transmits green light and means for supporting it

at a plurality of points so as to hold the intermediate portions in suspension.

3. In a thermo-telephone receiver, a heating element comprising a plurality of heating conductors of metal foil of a thickness of the order of gold leaf which transmits green light and means for holding the conductors in suspension.

4. In a thermo-telephone receiver a heating conductor of gold foil of such thickness that it transmits green light rays and

means for supporting it at a plurality of points intermediate its ends.

In testimony whereof we have signed our names to this specification in the presence 15 of two subscribing witnesses.

ALFRED WILLIAMS.
LEO D. WILLIAMS.
